HONING DEVICE

Kirke W. Connor, Detroit, Mich., assignor to
 Micromatic Hone Corporation, Detroit, Mich.,
 a corporation of Michigan

Application May 5, 1939, Serial No. 271,849

3 Claims. (Cl. 51—67)

This application is a continuation in part of my application, Serial No. 76,520, filed April 27, 1936, which issued as Patent No. 2,200,573 on May 14, 1940, and relates to honing methods and apparatus, and particularly to a honing method and device which employs a single abrading element which is rapidly oscillated and advanced relative to a surface to be honed to produce an accurate and highly polished surface.

In my Patent No. 2,108,029, dated February 8, 1938, and assigned to the assignee of the present invention, a method and apparatus are disclosed wherein a plurality of honing elements are rapidly reciprocated in timed relation to the speed of rotation of the tool to produce a predetermined angular intersection of the paths of abrasion during the time the tool and work are fed relative to each other. Certain features embodied in the invention of the above mentioned application appear in the present invention.

In the present invention a single honing element is employed which eliminates any binding and uneven wear on the stones which may occur when a plurality of the stones are employed in a single tool. It is substantially impossible to grade the abrading stones relative to hardness so that when a group of stones are employed, the wearing qualities of some are materially greater than those of others and, as a result, certain stones wear faster than others, causing a binding between the stones when depending upon each other for support within the work piece and uneven wearing of the stones.

Due to the rapid oscillation of the honing stone, a method of grinding is provided which simulates that of hand polishing wherein the hand is rapidly oscillated to move an abrading element over the surface to be honed. A feed movement is introduced between the oscillating stone and the work to extend the abrading operation uniformly over the surface.

Accordingly, the main objects of my invention are; to provide a method whereby an abrading stone is rapidly oscillated during the time a feed movement is provided between the work and the stone; to provide rapid reciprocation of a single honing element having an engaging surface congruent to that of the work and advancing the work and honing stone relative to each other to cover the entire surface to be finished; to provide a tiltable spindle having a single expansible abrading element thereon projecting into a work piece to contact the tapered surface of a cylindrical element through adjustment of the support for the spindle and reciprocating the spindle

and rotating the work piece in timed relation with each other; and in general, to provide apparatus for accurately machining surfaces to a high mirror finish, which is simple in construction, positive in operation and economical of manufacture.

Other objects and features of novelty of my invention will be either specifically pointed out or will become apparent when referring, for a better understanding of my invention, to the following description taken in conjunction with the following drawing, wherein:

Figure 1 is a view partially in section and partially in elevation of structure embodying features of my invention; and

Fig. 2 is a wiring diagram which may be employed for controlling the operation of the motors illustrated in Fig. 1.

In Fig. 1 I have illustrated the principles above set forth, that of rapidly oscillating a honing stone and providing a feed between the stone and work surface during such rapid oscillation, as embodied in a device adapted to hone conical objects. The work piece is illustrated as being a conical race 7 of a bearing which is supported in a holder 8 on a shaft 9 driven through a gear 11. The gear 11 may be driven through suitable pinions 6, by a motor 10, the speed of which may be regulated as pointed out hereinafter. The honing stone 12 is supported in a spindle 13, spring pressed outwardly from the axis of the spindle. The spindle is supported for reciprocation in a boss 14, and is keyed thereto by a key 15 to prevent rotation of the spindle relative to the boss. A head 16 is provided on the end of the spindle, being urged toward a cam 17 by a spring 18. The cam 17 is carried on a shaft 19 of a motor 21, the speed of which is adjustable. The boss 14 and motor 21 are mounted on a carriage 22 which is shiftable upon a table 23 by suitable means herein illustrated as a lead screw 24. The table 23 is tiltable relative to the table 25 on which the work support 8 is secured through a hinge 26 which interconnects the tables. A clamping nut 27 retains the table in position and through a quadrant 28 provides indicating means for setting off the relative angle of slope. The carriage 22 is retracted to have the stone 12 disengage the work piece 7 so that it may be removed and a new work piece inserted within the support 8. Thereafter the carriage 22 is advanced to have the stone 12 engage the surface of the work piece 7 and to be biased inwardly toward the axis of the spindle 13 upon further advancement of the carriage. The operation of

the motor 21 causes the stone 12 to be rapidly oscillated while the work piece 7 is rotated in predetermined relation to such oscillation.

Referring to Fig. 2, I have illustrated a wiring diagram wherein the motors 10 and 21 are disposed in series with rheostats 29 and switches 31 independently connecting the motors to a circuit. Through the adjustment of one or both of the rheostats the motors 10 and 21 may be changed in speed to vary the relative movement in reciprocation and rotation of the stone and work piece to thereby change the angle of crossing of the resulting scratch marks on the work piece surface. For various sizes of work pieces, for various types of metal and for different abrasive material, the angle of crossing of the scratch marks should be varied to produce the desirable type of honing and finishing.

In the wiring diagram of Fig. 2, I have illustrated in conjunction with the rheostats 29, solenoids 32 which cut in a predetermined amount of resistance when energized, to vary the speed of operation of the motors. The flow of current to the solenoids 32 is controlled by a time switch 33, which may be employed to actuate both of the solenoids, or individual time switches may be employed, one for each solenoid. As pointed out above, the desirable angle of scratch marks employed in a rough honing operation, for example, may vary materially from the preferred angle of crossing of the scratch marks to produce a fine finish, while operating with the same stone on the same work piece. Settings may be made on the rheostats to which the contact thereof is advanced through the energization of the solenoids through the operation of the time switch or switches. The switch or switches are set to operate upon the completion of the rough honing operation which thereby changes the type of honing from that employed during the roughing operation to that desired for the finishing operation. It therefore follows that I have illustrated a honing device employing a single honing stick which is moved radially from a spindle while being retained in fixed relation thereto. The spindle oscillates the stone across the tapered surface of a cylindrical work piece, the angle of the stone being adjusted to that of the taper. The spindle support has a pivotal connection and is locked in position by means of a quadrant, the scale of which checks the position of the stone. The work piece is rotated during the oscillation of the abrading stone while the abrading stone is fed parallel to the path of oscillation of the stone. The compound movement thus provided between the stone and the surface to be finished to accurate dimension may be varied by regulating the speed of the

motors driving the abrading stone in reciprocation and the work piece in rotation. A setting may be arranged by which the change from one speed of relative movement to another may occur between two different phases of operation, that of rough honing and that of home finishing a surface.

While I have described and illustrated but a single embodiment of my invention, it will be apparent to those skilled in the art, that various changes, omissions, additions, and substitutions may be made therein without departing from the spirit and scope of my invention as set forth in the accompanying claims.

15. What I claim is:

1. A honing device for machining a tapered surface including, in combination, a base, a support for a workpiece, means for rotating said support, a honing tool, a support for said honing tool hinged to said base and adjustable for positioning the slope of the honing tool, a table on said support on which the honing tool is mounted movable toward and away from said work-support, means on said table for reciprocating said tool, and a stone in said honing tool spring pressed outwardly against the surface of the workpiece to be honed.

2. A honing device for machining a tapered surface including, in combination, a base, a support for a workpiece on said base, means for rotating said support, a honing tool, an angularly adjustable support for said honing tool for positioning the slope thereof relative to the tapered surface of the workpiece, a table on said support on which the honing tool is mounted for movement toward and away from said work support, means on said table for reciprocating said tool, a honing stone in said honing tool, and means for urging said honing stone outwardly of said tool against the surface of the workpiece to be honed.

3. A honing device for machining a tapered surface including, in combination, a base, a support for a workpiece on said base, means for rotating said support, a honing tool, an angularly adjustable support for said honing tool for positioning the slope thereof relative to the tapered surface of the workpiece, a table on said support on which the honing tool is mounted for movement toward and away from said work support, means on said table for reciprocating said tool, a honing stone in said honing tool, means for urging said honing stone outwardly of said tool against the surface of the workpiece to be honed, and means for varying the relative driving speed of the workpiece in rotation and the abrasive stone in reciprocation.
